UNITED STATES PATENT OFFICE

111,027

DESIGN FOR SHEARS

Alden A. Lincoln, Bridgeport, Conn., assignor to
The Acme Shear Company, Bridgeport, Conn.,
a corporation of Connecticut

Application November 29, 1937, Serial No. 73,234

Term of patent 3½ years

To all whom it may concern:

Be it known that I, Alden A. Lincoln, a citizen of the United States, residing at Bridgeport, county of Fairfield, State of Connecticut, have invented a new, original, and ornamental Design for Shears, of which the following is a specification, reference being had to the accompanying drawing, forming part thereof.

Fig. 1 is a top plan view of a pair of shears, showing my new design;

Fig. 2 is a front elevation thereof;

Fig. 3 is a cross section on an enlarged scale substantially on line 3—3 of Fig. 2;

Fig. 4 is a similar section of the front blade only; and

Figs. 5 and 6 are similar sections taken substantially on lines 5—5 and 6—6 of Fig. 2 respectively.

The characteristic features of my design reside in the specific configurations of the horizontal and sloping fields on the sides of the shear blades, forming at the juncture of said fields a long gradual curve as shown in Fig. 2 of the drawing.

I claim:

The ornamental design for shears, substantially as shown and described.

ALDEN A. LINCOLN.
